W. I. TUTTLE

VALVE GRINDING APPARATUS

Filed April 29, 1922

Fig. 2.

Walter J. T. Cole Inventor
By his Attorney
W. J. Cole

UNITED STATES PATENT OFFICE.

WALTER I. TUTTLE, OF PROVIDENCE, RHODE ISLAND.

VALVE-GRINDING APPARATUS.

Application filed April 29, 1922. Serial No. 557,305.

To all whom it may concern:

Be it known that I, WALTER I. TUTTLE, a citizen of the United States, and a resident of Providence, in the county of Providence and State of Rhode Island, have invented an Improvement in Valve-Grinding Apparatus, of which the following is a specification.

This invention relates to valve grinding apparatus and the like. One of the objects thereof is to provide an apparatus of the above nature which is strong and reliable and well adapted to meet the conditions of hard, practical use. Another object is to provide an apparatus of the above nature which is readily adjustable to varying conditions of use and highly efficient at all times. Another object is to provide a construction of the above nature which is simple to operate and may be employed without the necessity of a great degree of manual skill. Other objects will be in part obvious and in part pointed out hereinafter.

The invention accordingly consists in the features of construction, combinations of elements and arrangements of parts as will be exemplified in the structure to be hereinafter described and the scope of the application of which will be indicated in the following claims.

In the accompanying drawing in which is shown one of the various possible embodiments of this invention,

Figure 1 is a side elevation of a valve grinding tool, certain parts being shown in section; and

Figure 2 is a detached sectional elevation viewed along the line 2-2 of Fig. 1 in the direction indicated by the arrows, certain parts being swung out of position.

Similar reference characters refer to similar parts in both views of the drawing.

As conducive to a clearer understanding of certain features of this invention, it may be here noted that in the process of grinding valves of the usual pop-valve type it is desirable to make use of a device which will reliably engage the valve head and by means of which the valve may be rapidly rotated first in one direction and then in the other. In the construction of these valves, it is common practice to provide the heads with a diametrical groove and in the central portion of this groove is commonly provided a small recess which marks the

center of the valve head. Other valve heads may be provided with a pair of diametrically opposed recesses while some are provided with both the groove and the recesses. Whichever of the above is provided it is 60 desirable to have at hand a tool which will reliably and efficiently engage the valve head to turn the same when it is necessary to perform an operation such as grinding, and the provision of such a tool is one of the dominant aims of this invention. 65

Referring now to Fig. 1 of the drawing in detail, there is shown a crank arm 10 provided with a suitable hand grip 11 at its eccentric portion and with a suitable handle 12 rotatably mounted at its upper end. Secured to the lower end of crank 10 in any suitable manner, as by means of a slot connection as shown and rivet 13, is a member 14, shown more clearly in Fig. 2, 70 the lower end of which is preferably shaped to form a blunt blade 15 which is adapted to be received in the diametrical slot in the top of a valve head, as shown diagrammatically in Fig. 2. At the central portion of blade 15 is preferably formed a downwardly projecting lug 17 which is adapted to be received in the recess in the center of the valve head groove. Thus, as blade 15 is inserted in the valve head groove, lug 17 will rest in the center mark or recess of the valve head and blade 15 will be automatically centered with respect to the axis of the valve. As the blade 15 is rotated by means of the eccentric handle 11, the axis of rotation of crank 10 may be held in alignment with the axis of rotation of the valve head by means of the handle 12. Lug 17 prevents any slipping of blade 15 in the valve head slot or groove and thus at all times the blade 15 is held centered with respect to the valve head and the axis of rotation of the crank 10 may be easily held in substantial alignment with the axis of the valve head. In this manner the grinding operation is greatly facilitated. 90

The member 14 is preferably provided with a curved portion 18 forming a transverse groove on one side thereof in which rest a pair of overlapping arms 19 and 20. Arms 19 and 20 may be semicircular in cross section, as shown, fitting snugly together and they are preferably clamped against member 14 by a link 21 which is secured to the member 14 by means of screws 22 and 100

23, one of which, as 23, may be a thumb screw. Arms 19 and 20 are provided with a pair of extensions 24 and 25 respectively which extend at substantially right angles thereto and are preferably shaped at their ends to provide a pair of lugs 26 and 27 which are adapted to be received in a pair of diametrically opposed recesses in the top of the valve head, as shown diagrammatically in Fig. 1.

Lugs 26 and 27 in operative position as shown in Fig. 1 extend below the blade 15 and lug 17, and in order to make use of the latter, the arms 24 and 25 may be swung 15 out of operative position as shown in Fig. 2 or may be completely removed by simply loosening thumb screw 23. Lugs 26 and 27 may be spaced from each other as desired to suit the spacing between the recesses 20 in the valve head since they are formed on independent members 19 and 20 which may be loosened simply by a slight turn of screw 23 and may be moved relative to each other. The valve head may be rotated by means of 25 handle 11 as described above and the axis of the crank 10 may be held in alignment with the valve axis by means of handle 12, the two lugs 26 and 27 in this instance serving to center the device with respect to the 30 valve head.

Moreover, when it is desired to use one of the devices for engaging the valve head, the other is automatically made ineffective as a valve-head engaging device. Thus, for 35 example, if the lugs 26 and 27 are intended for engagement with the valve head, the swinging of the arms 24 and 25 into operative or engaging position as shown in Fig. 1 automatically raises the blade 15 and its 40 associated parts into ineffective and unobtrusive position.

It will thus be seen that there is herein provided a device which is particularly adapted to meet varying conditions in practical use and which is capable of thoroughly efficient operation at all times regardless of the conditions met with.

As many possible embodiments might be made of the above invention and as many 50 changes might be made in the embodiment above set forth, it is to be understood that all matter hereinbefore set forth or shown in the accompanying drawing is to be interpreted as illustrative and not in a limiting 55 sense.

I claim as my invention:

1. In valve grinding apparatus, in combination, a blade adapted to engage a slot in the top of a valve head, a pair of downwardly extending lugs associated with said blade adapted to engage a pair of diametrically opposed openings in the top of a valve head, means for rotating said blade and said lugs, and means adapted to permit swinging 60 of one of said lugs out of operative position.

tion to facilitate the use of said blade, the other of said lugs being connected to swing therewith.

2. In valve grinding apparatus, in combination, a blade adapted to engage a slot 70 in the top of a valve head, a pair of downwardly extending lugs associated with said blade adapted to engage a pair of diametrically opposed openings in the top of a valve head, one of said engaging devices when in 75 operative position being of greater length than the other, whereby said other device is rendered ineffective, means for rotating said blade and said lugs, and means for swinging the device of greater length upwardly as a unit and out of operative position to render the other device effective.

3. In valve grinding apparatus, in combination, a member having at its lower end a blade adapted to be received in a groove 85 formed in the top of a valve head, a pair of arms removably clamped upon said member and having a pair of downwardly extending lugs adapted to engage diametrically opposed recesses in the top of said valve head, said arms being adapted to be rotated as a unit to swing said lugs out of operative position to facilitate the use of said blade and means for rotating about a common axis said blade and said pair of arms.

4. In valve grinding apparatus, in combination, a member having at its lower end a blade adapted to be received in a groove 100 in the top of a valve head, said blade having a projection adapted to enter a recess in the bottom of said groove to center said blade with respect to said valve head, a pair of overlapping members having downwardly extending lugs adapted to engage a pair of diametrically opposed recesses in 105 said valve head, a member spaced from said first member and clamping said two overlapping members to said first member to permit relative sliding of said overlapping members for adjustable spacing of said lugs and to permit removal of said pair of members to facilitate the use of said blade member, and means for rotating said 110 blade member and said pair of members about a common axis to turn said valve head.

5. In valve grinding apparatus, in combination, a blade adapted to fit into a slot 115 in the top of a valve head, a member spaced from and removably secured to a portion of said blade, and a device clamped between said member and said blade having a pair of downwardly projecting parts adapted to engage a pair of oppositely disposed recesses in said valve head, said device being adapted to be moved relative to said member and said blade to move said projecting parts into inoperative position.

6. In valve grinding apparatus, in com-

bination, a blade adapted to fit into a slot in the top of a valve head, a pair of overlapping members of semicircular cross section having downwardly extending projections adapted to engage a pair of diametrically opposed recesses in the top of said valve head, means connecting said members to a portion of said blade to permit their swinging as a unit about a substantially

lateral axis to move said projections out of operative position, and means for rotating said blade and said projections about a vertical axis.

In testimony whereof, I have signed my name to this specification this 24th day of 15 April, 1922.

WALTER I. TUTTLE.
